T. MARTIN

LOOM

Filed April 15, 1926

WITNESS

Wm. M. Bell

INVENTOR

Traugott Martin,
BY *John H. Ward*
ATTORNEY

UNITED STATES PATENT OFFICE.

TRAUGOTT MARTIN, OF PATERSON, NEW JERSEY.

LOOM.

Application filed April 15, 1926. Serial No. 102,122.

This invention relates to improvements in looms, especially of the narrow ware class in which the shuttles are arranged in banks one above another and the entire complement of 5 shuttles, subject to the control of a pattern or equivalent mechanism, is moved up or down from time to time so as to discontinue the weaving action of the shuttles in one bank and start the shuttles in an adjoining bank to operate. Examples of looms of 10 this type are afforded by the Schaum Patent #1,278,226 and my own Patent #1,498,396. Sometimes the structure including the several banks of shuttles is allowed to fall be- 15 cause of some fault in the mechanism which controls it, and when this happens, the loom otherwise continuing in operation, the result is disastrous to the warp and goods then in the loom, causing irreparable damage there- 20 to and sometimes great loss. It is the object of this invention to provide automatic means for stopping the loom when said structure is thus allowed accidentally to fall.

In the drawing—

25 Fig. 1 is a side elevation of sufficient of a loom embodying my invention to illustrate the latter;

Fig. 2 is a front elevation of an end portion of what is shown in Fig. 1, the shuttles 30 being omitted; and

Fig. 3 is a fragmentary side elevation with parts of the loom projecting beyond the near side-frame in vertical section to show certain details of the invention more clearly.

35 In the loom-frame 1 are pivotally supported pairs of parallel links 2 which in turn pivotally support castings 3 which carry the lay or batten 4. Only one side or side-frame of the loom-frame, one pair of links and one 40 casting are shown, but it will be understood that there will be two or more of each ac- cording to the width, viewed from front or rear, of the loom. The castings 3 have connected to them the pitmen 5 and through 45 them, from the wheels 5^x (only the near one being shown) on the main shaft 5^y, they are reciprocated forward and back substantially as usual in looms. As will appear, the ob- ject in supporting the batten structure 3—4 50 by pairs of pivoted links is always to main- tain it in a vertical position in its forward and backward movement; this, however, is

also old in the particular type of loom to which the present invention relates.

A shuttle frame 6 is arranged to slide vertically in the batten structure, having in the present case top and bottom fittings 8 which are guided on the vertical rods 9 which may be regarded as parts of the batten structure. The shuttles are shown at 10 in two sets of 60 superposed banks, in this case there being two superposed banks to a set, or in other words, two superposed banks to each weaving plane 10^a. The means for mounting them in the frame 6 and the means for reciprocating them toward and from the observer in Fig. 1, or laterally and horizontally in Fig. 2, are entirely immaterial to the present invention and may follow any well-known construction and operate in any well-known 70 way.

The frame 6 is moved vertically from any suitable pattern or equivalent mechanism, as in the mentioned patents, a part of 75 which may be afforded in the present instance by the member 11 which moves up and down when called and to which is connected, through a link 12, a lever 13 fulcrumed on a rock-shaft 14 and in turn pivotally connected with the frame 6 through 80 the link-connection 15; so much of the lever 13 as is at the right of the rock-shaft in Fig. 1, together with link connection 15, will be duplicated at the far end of the loom in said figure, it will be understood, and such duplicate-lever, not shown, will of course be fixed 85 to the rock-shaft 14. A spring 15^a connects the member 11 with some fixed point 15^b and serves to counterbalance the weight of those parts which are carried by the forward end 90 of lever 13 and the mentioned duplicate-lever at the far end of the loom.

As already suggested, sometimes in these looms the frame 6 assumes an abnormally 95 low position, below that indicated by the dotted outline *x* in Fig. 3. The structure including frame 6 and the shuttles is quite heavy, and if some fault occurs in the pattern mechanism or in some part of the train connecting it with said structure the latter 100 will fall. If the loom is at the time going and producing goods it invariably means a bad smash, involving destruction of the warp and woven goods and usually great loss to

the manufacturer, especially if the loom is of large capacity. For the prevention of injurious action of the loom in such an emergency I provide means to stop the operation 5 immediately as follows:

The gear 5^x on the main shaft 5^y is in mesh with a pinion 16 on the drive-shaft 17. It is not material how this drive-shaft is driven, but in the present case it is equipped 10 with fast and loose pulleys 18 and 19 around which may extend a driving belt 20 shiftable from one to the other pulley. The shifting of the belt is controlled by a belt-shifter 21 which is an upstanding arm on a rock-shaft 15 22 journaled in the loom-frame and having at its forward end an upstanding arm 23, 21, 22 and 23 being in effect a shipper lever. Arm 23 is engaged with the usual slideable bar 24 which is suitably guided and extends 20 across the front of the loom in convenient reach of the weaver for starting and stopping the machine.

On a pin 25 in the frame of the loom is fulcrumed a detent lever 26 which extends 25 between the batten 4 and the frame 6, its rear end being normally held elevated by a spring 27. In a bracket 28 projecting laterally from the side frame is fulcrumed a trip lever 29 whose upper end has a bunter 29^a adapted when the trip lever moves to the right in Fig. 2 to strike the arm 23 of the shipper lever to shift the same to the position for stopping the loom. This movement of the trip lever is effected by a spring 30 which connects its lower end (below its fulcrum) with the bracket 28. There is a 30 pawl 31 pivoted to the trip lever and it is normally held by a spring 32, connecting it with the trip lever, so as to bear upwardly 35 against a guiding pin 33 which may project forward from the loom frame (Fig. 3). This pawl has a notch 31^a in which it engages the detent lever 26 when the trip lever is shifted to the left in Fig. 2 and thus 40 cocked.

For starting or stopping the loom the operator shifts the bar 24 to the left or right, respectively, in Fig. 2, which through the shipper lever establishes the belt on the fast or loose pulleys as the case may be. Of course the trip lever at this time will be in 45 cocked position (Fig. 2), because it is assumed that the loom is operating normally, i. e., that the shuttle frame is clear of lever 50 26, which is thus held by its spring 27 engaged with the pawl 31. If for any reason the shuttle frame 6 should fall and cause the detent lever to release the pawl 31 the trip lever 29 will be caused by its spring 30 to impinge, with its bunter 29^a, against the 55 arm 23 of the shipper lever, instantly stopping the loom.

In the present example the shuttle frame 6, positively moved in one direction by the 60 means 11-12-13-15, is urged in the other

direction by gravity,—in other words it tends normally to fall. But the invention is applicable whether the mechanism is so constructed that said frame normally tends to rise or fall or what medium is responsible ⁷⁰ for such tendency. Of course any other form of stopping means than the means 11-12-13-15 may be resorted to.

Having thus fully described my invention what I claim and desire to secure by Letters Patent is:

1. A loom of the class described including supporting means, driving means, an up-and-down-movable structure arranged in the supporting means and including superposed 80 shuttles arranged in the supporting means and normally urged in one direction, means to move said structure in the opposite direction normally adapted to restrain the same against movement in the first direction past a given limit, and means, having a controlling part arranged in the path of movement of said structure past said limit and to be actuated by said structure on its passing said limit, for causing stopping of the driving means.

2. A loom of the class described including a frame, going means therein including a reciprocating batten structure, an up-and-down-movable structure in the batten structure, including superposed shuttles and normally urged in one direction, means to move the second structure in the opposite direction normally adapted to restrain the same against movement past a given limit in the first direction, and means, having a controlling part arranged in the path of movement of said second structure past said limit and to be actuated by said second structure on its passing said limit, for causing stopping of the going means.

3. A loom of the class described including supporting means, driving means, an up-and-down-movable structure arranged in the supporting means and including superposed 110 shuttles arranged in the supporting means and normally urged in one direction, means to move said structure in the opposite direction normally adapted to restrain the same against movement in the first direction past a given limit, back-and-forth movable means for stopping the driving means normally urged in one direction to stop the same, and a detent normally restraining the last-named means against such movement and arranged in the path of movement of said structure past said limit and adapted to be moved by said structure on its passing said limit to release said last-named means.

4. A loom of the class described including 125 a frame, going means therein including a reciprocating batten structure, an up-and-down-movable structure in the batten structure, including superposed shuttles and normally urged in one direction, means to move 130

the second structure in the opposite direction normally adapted to restrain the same against movement past a given limit in the first direction, back-and-forth-movable means for stopping the going means normally urged in one direction to stop the same, and a detent normally restraining the last-named means against such movement and ar-

ranged in the path of movement of said second structure past said limit and adapted to be moved by said second structure on its passing said limit to release said last-named means.

In testimony whereof I affix my signature.

TRAUGOTT MARTIN.
